UNITED STATES PATENT OFFICE.

ELIZABETH AMSLER-LAFFON, OF NEW CITY, NEW YORK.

DESIGN FOR SURFACE ORNAMENTATION OF FABRIC.

52,936.

Specification for Design.

Patented Feb. 4, 1919.

Application filed December 11, 1918. Serial No. 266,338. Term of patent $3\frac{1}{2}$ years.

To all whom it may concern:

Be it known that I, ELIZABETH AMSLER-LAFFON, a citizen of Switzerland, residing at S. P. Davies' farm, in New City, in the county of Rockland and State of New York, have invented a new, original, and ornamental Design for Surface Ornamentation of Fabric, of which the following is a specification, reference being had to the accompanying drawing, forming part thereof.

The figure is a view of my new design for surface ornamentation embodied in a piece of fabric.

I claim:

The ornamental design for surface ornamentation of fabric, as shown.

ELIZABETH AMSLER-LAFFON.
